UNITED STATES PATENT OFFICE.

AMEL F. BAHR AND OTTO B. BAHR, OF MARION, INDIANA.

PAPER-PULP MILL.

946,752.

Specification of Letters Patent. Patented Jan. 18, 1910.

Application filed August 23, 1909. Serial No. 514,326.

To all whom it may concern:

Be it known that we, AMEL F. BAHR and Otto B. BAHR, citizens of the United States, residing at Marion, in the county of Grant 5 and State of Indiana, have invented certain new and useful Improvements in Paper-Pulp Mills, of which the following is a specification, reference being had therein to the accompanying drawing.

10 Our invention relates to improvements in paper pulp mills hereinafter described in this specification and particularly pointed out in the claim.

Heretofore paper pulp mills have been 15 constructed with shells built up of wood sections in the form of a hollow truncated cone in or between each section of which were secured stationary knives which projected radially inwardly from the inner surface 20 of the shell. This shell deteriorated under the action of the moisture of the pulp passing through the mill, and it became necessary at times to replace the shell with a new shell which was built up in the casing of 25 the mill which was an expensive operation and necessitated skilled labor and experience in this class of work to make the repair or renewal.

30 The object of this invention is to provide a removable metallic shell for paper pulp mills that will be to a great degree impervious to moisture and the acidulated fluid in the pulp mixture passing through the mill and that may be keyed and expanded to be 35 secured in position in the interior of the mill, and also, to provide a simple means for expanding the sections of which the shell is composed separately and independently of each other to secure them in their fixed positions in the casing, also, to construct the 40 internal grinding teeth of the shell integral with the shell. We attain these objects by means of the invention illustrated in the accompanying drawings in which like numerals of references designate like parts 45 throughout the several views.

Figure 1. is a longitudinal sectional elevation of the mill taken along the line 1—1 in Fig. 2; Fig. 2. is a transverse sectional elevation of the same taken along the line 2—2 in Fig. 1; Fig. 3. is an enlarged detail transverse section of the guide bars of the sliding bearing taken along the line 3—3 in Fig. 1; Fig. 4. is a detail side elevation of 50 the revolving center or plug of the mill; Fig. 5. is an end elevation of the larger end 55

of the revolving center or plug of the mill; Fig. 6. is a similar view of the smaller end of the revolving center or plug of the mill; Fig. 7. is an enlarged detail side elevation 60 of the exterior of the shell; Fig. 8. is a development or envelop of a portion of one of the sections of the shell showing the arrangement of the interior teeth thereof; and Fig. 9. is a section of the same taken along the line 9—9 in Fig. 8.

The outer casing 1 of the mill is formed like a hollow truncated cone and is preferably constructed of cast iron with its larger end open and its smaller end closed by the integral cover portion 2. The larger open end portion of the casing 1 is provided with a removable cover 3 which is fitted to the face of the flange portion 4 to form a close joint, and to said flange portion is securely bolted the cover portion 3 by the bolts 5 so as to be removable.

Centrally on the integral end cover 2 and the removable cover 3 are formed the shaft bearings 6 and 7 which are bored to receive 80 the packing glands 8 whereby the joints between the said bearings and the peripheral surface of the shaft 10, are rendered water tight. The casing 1 is provided with the feet 9 whereby it is supported in horizontal position. The ends of the shaft 10 are prolonged to project beyond the glands 8. The prolonged end of the shaft 10 projecting from the smaller closed end of the casing 1 is supported in the bearing 11 and the outer bearing 12 formed integral with the standard 13. The other prolonged end of the shaft is provided with a grooved portion 14 which is fitted in the sliding bearing 15 so as to take up the end thrust on the shaft when moving the latter longitudinally.

The sliding bearing 15 is provided with the bearing shoulders 16 which rest upon the surfaces of the bearing ways of the 100 guide bars 17. The ends of the guide bars 17 are provided with the integral feet 18 which are fitted and securely bolted in position to the cover 3. The cross-bar 19 is formed integral with the guide bars 17 and 105 is bored and threaded to receive the screw 20 whereby the shaft 10 is moved longitudinally to adjust the position of the revolving center or plug relatively to the shell.

The revolving center or plug is composed 110 of the centers or end spiders 21 and 22 which are keyed or otherwise secured in

position on the shaft 10 to turn with the latter, and the staves 23 which are built up around the peripheries of the centers 21 and 22 and secured thereto after which said center is turned truly on its outer periphery to reduce the staves to a true conical surface, and set in between said staves 23 and secured in position at their proper distances apart are the longitudinally extending knives 24, see particularly Figs: 3, 4, and 5.

The knives 24 project beyond the outer peripheral surface of the revolving center or plug, so as to coöperate with the knives 15 or teeth 29 of the stationary shell.

The stationary or non-revolute shell is constructed of a metal, preferably an alloy composed of manganese, pig iron and steel, and may be divided into three sections or 20 parts, and consists of the end sections 25 and 26 and the intermediate section 27, each of which sections is constructed in the form of a truncated cone or is tapered on its exterior surface to fit into the interior bore of 25 the casing 1 and each of said sections is divided or split longitudinally at one side and between these divided portions is driven an expanding key 28 whereby the sections each are expanded in the casing 1 to be 30 tightly held in position therein to be prevented from turning with the revolving center or plug as it is revolved.

Each section of the shell is provided with teeth or knives 29, which are formed integral with the body portions 25, 26 and 35 27 of the shell and said teeth or knives coöperate with the teeth 24 of the revolving center or plug to reduce the paper pulp into the finely divided state required in paper 40 manufacture. The teeth or knives 29 of the shell are inclined to the direction of the axis of the shell or are arranged to extend helically, as shown in the developed view of a section in Fig. 8.

45 Each of the shell sections 25, 26 and 27 is provided with steadyng bolts 29^a, which are situated diametrically opposite the key or slit and the said bolts are provided for the purpose of holding the sections in position 50 in the casing 1 while driving the keys 28 home to expand the sections in the casing 1 to snugly fit therein.

The shaft 10 and the revolving plug or center are moved longitudinally by the screw 20 when it is necessary to move the cutting 55 edges of the knives 24 nearer to the cutting edges of the teeth or knives 29 to adjust the mill to reduce the pulp to a required degree of fineness, or when it is necessary to adjust the knives on account of wear. The 60 shaft 10 on which the revolving center or plug is mounted is driven by the belt pulley 30.

The inlet pipe 31 supplies the paper pulp to the mill to be reduced to the finely divided state and the outlet pipe 32 carries the reduced paper pulp that has passed through and undergone the operation of reduction or grinding from the mill. On the end portion of the screw 20 is secured 65 a hand-wheel 33 whereby the screw 20 is revolved to move the bearing 15 when adjusting the knives 24 in position relatively to the knives 29.

We claim:—

In a paper pulp mill, the combination with an outer conical casing having a smaller closed end and a larger open end, a removable cover on said open end, a 80 conical revolving center or plug situated centrally and extending longitudinally in said casing, longitudinally extending knives projecting from the peripheral surface of the said revolving center or plug, of a shell composed of a plurality of sections of a 85 truncated cone form and each section composed of an integral piece of metal and each section provided with a longitudinally extending peripheral dividing slit, keys fitted into each slit of said sections, whereby said 90 sections are independently expanded to fit tightly in said outer casing, integral teeth projecting from the interior peripheral surface of said shell, and anchor bolts passing through said shell and said casing, whereby 95 said shells are held in their relative positions in said casing.

In testimony whereof we affix our signatures in presence of two witnesses.

AMEL F. BAHR.
OTTO B. BAHR.
